TOOL

Filed Oct. 10, 1932

UNITED STATES PATENT OFFICE

HENRY F. HOWARD, OF DETROIT, MICHIGAN, ASSIGNOR TO WHITMAN & BARNES,
INCORPORATED, OF DETROIT, MICHIGAN, A CORPORATION OF MICHIGAN

TOOL

Application filed October 10, 1932. Serial No. 637,157.

This invention relates generally to tool holders and refers more particularly to a holder for cutting tools such as counterbores having heads provided with cutting blades 5 and axially extending shanks.

One of the essential objects of the invention is to provide a holder of this type in which means is provided for direct engagement with the head of the tool to drive the 10 same, and other means is provided for gripping the shank so that the direct drive aforesaid will be maintained.

Another object is to provide a holder that is adapted to interchangeably receive a 15 greater range of tools and that is so constructed that the driving connection and gripping relationship referred to may be easily and quickly established by hand without the aid of wrenches, keys or other implements.

Another object is to provide a holder in which a minimum of parts are employed to accomplish the desired results.

Another object is to provide a holder that 25 is sturdy and compact and that is free from objectionable threads and adjustments.

Another object is to provide a holder that is simple in construction and can be manufactured at a comparatively low cost.

Other objects, advantages and novel details of construction of this invention will be made more apparent as this description proceeds, especially when considered in connection with the accompanying drawing, where- 35 in:

Figure 1 is an elevation of a counterboring tool and holder therefor embodying my invention, with parts broken away and in section;

Figure 2 is a view taken at substantially right angles to Figure 1 with parts broken away and in section;

Figure 3 is a sectional view taken on the line 3—3 of Figure 2;

Figure 4 is a sectional view taken on the line 4—4 of Figure 1;

Figure 5 is a perspective view of the tool receiving member;

Figure 6 is a perspective view of the sleeve;

Figure 7 is a perspective view of the counterbore tool;

Figure 8 is a perspective view of the detent;

Figure 9 is a side elevation of the detent;

Figure 10 is a top plan view of the detent; Figure 11 is an end elevation of the detent; Figure 12 is an enlarged portion of Figure 2.

Referring now to the drawing, A is the counterboring tool and B is the holder therefor of an assembly embodying my invention. As shown, the tool A has a shank 1 of cylindrical formation and is provided at one end of said shank with an enlarged head 2 having cutting blades 3 thereon. Preferably the shank 1 has the usual bore 4 for a pilot (not shown) and is provided at one end with a transversely extending groove 5 for the usual pilot retaining nut (not shown). The holder B comprises only three parts, namely a tool receiving member 6, sleeve 7 and locking detent 8. Preferably the tool receiving member 6 has a shank 9 of conventional design, an annular flange 10 at the inner end of said shank, a cylindrical portion 11 beyond and having a socket 11' therein, and a pair of driving lugs 12 and 13 respectively projecting endwise from diametrically opposite points of the free end of the cylindrical portion 11. The sleeve 7 is substantially equal in length to and is mounted to turn on the cylindrical portion 11 of the tool receiving member 6. Preferably this sleeve 7 is provided at opposite ends thereof with knurled portions 14 and 15 respectively and is provided between said knurled portions with a smooth portion 16 having a circumferentially extending slot 17 and a circumferentially extending tongue 18 projecting from one end of the slot. As shown, the side walls 19 and 20 respectively of the slot converge slightly from the fixed end of the tongue to points slightly in advance of the free end thereof, while opposite longitudinal edges 21 and 22 respectively of the tongue converge from the fixed to the free ends thereof and are preferably parallel to the side walls 19 and 20 of the slot. At its free end the tongue 18 is provided with an inwardly projecting longitudinally extending cam portion 23 which is normally at one side of the detent 8 in a circumferentially extending slot 24 in the cylindrical portion 11 of the tool receiving member. As shown, one side 25 of the cam portion is inclined or beveled for engagement with the correspondingly inclined or beveled side wall 26 of the slot 24, while the other side 27 of the cam portion constitutes an extension of the longi-

tudinal edge 21 of the tongue and is disposed at substantially right angles to the axis of the sleeve. The detent 8 is preferably semi-circular in configuration and is mounted for 5 tilting movement in the slot 24. As shown, the detent 8 tapers from one end to the other and has rounded ends 30 and 31 respectively engaging curved ends 32 and 33 respectively of the slot. Preferably one side 34 of the detent and the adjacent wall 35 of the slot are 10 normally substantially parallel and extend at substantially right angles to the axis of the cylindrical portion 11, while the other side 36 of the detent is inclined downwardly 15 and inwardly and is adapted to be engaged by the side 27 of the cam portion 23 of the tongue. Thus when the holder parts are assembled the shank 1 of the tool may be inserted into the socket 11' so that the driving 20 lugs 12 and 13 will be received in correspondingly shaped recesses 12' and 13' in the head 2, whereupon the sleeve 7 may be turned by hand to cause the cam 23 of the tongue 18 to tilt the detent 8 so that the edge 40 thereof will firmly engage and hold the tool shank 1. Consequently when the assembly 25 is in use the rotary motion imparted to the shank 9 will be transmitted by the lugs 12 and 13 directly to the head 2 having the cutting blades 3 thereon, while the locking engagement 30 between the detent 8 and the shank 1 will function only to prevent the tool shank from moving longitudinally in or falling out of the socket 11'. Thus the direct connection 35 from the shank 9 of the tool receiving member to the head 2 of the tool, instead of through the tool shank 1, insures a stronger and more positive drive and permits the detent 8 to function independently 40 as a locking element. In this connection it will be noted that the detent 8 is adapted to engage the periphery of the tool shank 1, hence such tool shanks do not have to be specially constructed or grooved to accommodate pins, keys and the like. As a result 45 a holder constructed in accordance with my invention is adapted to interchangeably receive a greater range of tools.

After being used the tool A may be removed from the holder B by simply turning the sleeve 7 by hand in the opposite direction so that the detent 8 will be released by the cam 23. In this connection it will be noted that the tongue 18 in addition to actuating the detent cooperates with the wall 25 of the slot 24 to prevent axial displacement of the sleeve 7 from the cylindrical portion 11 of the tool receiving member. However, if desired the sleeve 7 may be removed from the cylindrical portion 11 of the tool receiving member by a proper implement such as

a spanner wrench (not shown). Preferably suitable holes 43 and 44 respectively are provided in the sleeve 7 at diametrically opposite points thereof for this purpose.

What I claim as my invention is:

1. In a tool holder, a member having a socket portion for receiving the shank of a tool and provided intermediate the ends of said socket portion with a circumferentially extending slot for the reception of a tiltable detent, a sleeve on the socket portion and having a tongue provided in the slot with a cam portion, and means for holding a tool shank in the socket portion aforesaid, including a detent of substantially semi-circular configuration mounted to tilt in the slot and actuatable by the cam portion of the sleeve tongue. 75

2. A tool holder including a member having a socket portion for receiving the shank of a tool and provided in said portion with a transversely extending slot, means for gripping the tool shank in the socket, including a detent extending longitudinally of the slot and mounted to swing lengthwise of the socket portion, and actuating means for the gripping means including a member movable circumferentially of the socket portion and having a part in the slot and engageable with the detent. 85

3. A tool holder including a member having a socket portion for receiving a shank of a tool and provided in one side of said portion with a circumferentially extending slot having opposite side walls thereof extending substantially at right angles to the axis of the socket portion, and means for gripping the tool shank in the socket portion including a member having its ends pivoted in opposite ends of the slot and having the portion remote from the pivots movable lengthwise of the socket portion between the transversely extending walls aforesaid of the slot, and means associated with the socket portion for actuating said gripping means. 100

4. In a tool holder, a member having a socket for receiving a tool shank and provided intermediate the ends of said socket with a circumferentially extending slot, and means for holding a tool shank in the socket including a longitudinally curved detent having opposite ends thereof journaled in opposite ends of the slot so that the intermediate portion thereof is movable in the arc of a circle longitudinally of the socket between opposite walls of the slot, and actuating means for the detent including means movable about the socket and having a part movable in said slot between a wall thereof and one side of said intermediate portion. 115

In testimony whereof I affix my signature.
HENRY F. HOWARD.
